SAPPHIRE GRINDING MEANS

Frank L. Capps, New York, N. Y.

Application January 13, 1939, Serial No. 250,668

9 Claims. (Cl. 51—103)

This invention relates to new and useful improvements in the art of sound recording and has particular relation to a means and method of automatically grinding into cylindrical shapes sapphires which are polygonal in transverse section and which are to be made into sound recording styli.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings—

Fig. 1 is a front elevational view of a machine made in accordance with the invention;

Fig. 2 is a side elevational view of said machine, the view being taken looking from the right in Fig. 1;

Fig. 3 is a top plan view of the machine;

Fig. 4 is a side elevational view of the machine, the view being taken as looking from the left in Fig. 1;

Fig. 5 is a detail elevational view showing a mounting device employed;

Fig. 6 is a view taken at right angles to Fig. 5 and showing the means mounted by the device of Fig. 5;

Fig. 7 is an enlarged plan view showing a portion of the grinding wheel and certain parts associated therewith;

Fig. 8 is a detail view on an enlarged scale showing the mounting of a lever employed;

Fig. 9 is an enlarged front elevational view of a portion of the machine;

Fig. 10 is a detail sectional view taken as along the line 10—10 of Fig. 9;

Fig. 11 is a detail sectional view, on an enlarged scale, of the grinding wheel employed; and

Fig. 12 is a front elevational view showing a modified construction of grinding wheel.

Referring in detail to the drawings the machine of the invention is shown as mounted on any suitable base 10. The machine comprises a supporting structure generally designated 11. Structure 11 includes a portion 12 secured to the base 10 by means of screws 13 and an upright portion 14 carrying laterally extending angularly related portions 15 and 16 and also carrying a pair of spaced arms 17 and 18. Arms

17 and 18 at their upper ends include bearing portions 19 and 20 respectively.

Lateral extension 15 has a slot 21 passing vertically therethrough and mounts a bifurcated bracket 22 having a threaded stud 23 passing through the slot 21 and equipped with a securing nut 24. Bracket 22 includes vertical arms 25 and 26 at their upper ends having split bearing-like portions 27 and 28 secured together as by screws 29. Portions 27 and 28 support a shaft-like member 30 and hold the same against movement when the screws 29 are tightened to have such portions grip or clamp the member. Obviously the bracket 22 together with its bearing-like portions 27 and 28 is adjustable along the extension 15.

A bracket-like member 31 is also secured to the extension 15, a bolt 32 passing through the slot 21 together with a nut 33 on the lower end 20 of said bolt serving to secure the member 31 in the desired position on the extension. Member 31 carries a vertically disposed rod 34 by an upper portion of which is supported a water or other liquid container 35. The container is secured to the rod by means of a device 36 having one end portion clamped about the rod by a means 37 and having its other end portion 38 comprising a rest for the container.

Mounted on the base 10 is an electric motor 39 having a pulley 40 secured to the shaft thereof. A pulley 41 on a shaft 42, mounted in the bearings 19 and 20, has trained thereover a belt 43 which belt is also trained over the pulley 40 whereby the shaft 42 is driven by the motor 39. Mounted on the shaft 42 to rotate therewith are pulleys 44 and 45 and a grinding wheel 46 the purpose of all of which will appear.

The extreme upper portion 47 of the vertical rod 34 has passing therethrough a threaded stud 48 carrying a shaft supporting device generally designated 49 and shown best in Figs. 5 and 6. The device 49 includes a plate-like portion 50 to which the stud 48 is attached and such portion carries a pair of parts 51 and 52 into the outer or free ends of which is threaded a screw 53 adapted when tightened to draw such parts toward one another. A tube 54 passes between the parts 51 and 52 and when the screw 53 is tightened such tube is clamping held.

On the member 48 between the plate-like portion 50 and the rod 34 is a part 55 including a plate-like portion 56 facing the portion 50. The arrangement is such that on loosening of a nut 57 on the stud 48 the device 49 may be rotated with the stud as an axis. However, this

is for the purpose of adjustment only and when the parts have been adjusted as will hereinafter appear the nut 57 is tightened and remains in that condition.

Passing through and rotatable in the tube 54 is a shaft 58 carrying a roller 59 of rubber or other frictional material. The roller is secured to the forward end of the shaft 58 and to the rear end of such shaft is secured a worm gear 60 meshing with a worm 61, the worm and worm gear being enclosed in a casing 62. Since the device 49 may be adjusted on loosening of screw 48 and as the shaft 58 is movable with the device it will be clear that the roller may be swung between the full and dotted line positions of Fig. 2.

Roller 59 cooperates with the wheel 46 during the grinding of a sapphire as will appear and for the purpose of such cooperation the roller is rotated in a direction transverse or across the direction of rotation of the wheel. A bracket member 63 extends forwardly from the upright 14 and carries a pulley 64 and a shaft 65 on which the pulley is secured. Trained over the pulley 64 and the pulley 45 on the shaft 42 is a belt 66 whereby the shaft 65 is driven from the shaft 42. Attached to shaft 65 is one end of a flexible shaft 67 the other end of which is connected in driving relation with the worm 61. Thus the roller 59 is being driven when ever the grinding wheel 46 is rotating.

Mounted on the extension 16 of the support 11 is a gear box 68 containing a reduction gearing (not shown) including a pair of shafts 69 and 70. Secured to the shaft 69 is a pulley 71 over which is trained a belt 72 trained over and driven by the pulley 44 on the shaft 42. Through the mentioned reduction gearing (not shown) the shaft 69 drives the shaft 70 and the latter, at the side of the gear box opposite that at which the pulley 71 is located, carries a cam generally designated 73 the purpose of which will be fully set forth.

The stationary shaft 30 is concentric with the shaft 42 and mounted on the shaft 30, to turn thereabout, is a bracket 74 including a block or arm 75 having a tubular projection 76 (see Fig. 8) concentric with said shaft. An L-shaped lever having portions 77 and 78 is mounted on the projection 76 but is not secured thereto although having a friction fit thereon. The lever portion 77 mounts a pin 79 carrying a roller 79a cooperating with the cam 73 whereby the lever is rocked about the shaft 30 at predetermined times as will appear.

Lever arm 78 extends longitudinally of the block 75 and has an arcuate slot 80 therein through which extends a set screw 81 threaded into the block. With this arrangement on loosening of the set screw the lever may be adjusted relative to block 75 and shaft 30 after which the screw will be tightened. A coil spring 82 secured at its upper end to a pin 83 on the lever arm 77 has its lower end secured to the supporting structure 11 and serves to maintain the roller 79a against the cam 73.

Grinding wheel 46 comprises a mounting or carrier portion 84 of steel or other hard material and against one side of which is secured a disc 85 of copper or other relatively soft metal. Disc 85 has a groove 86 in its peripheral edge and such groove is to partly receive a sapphire to be ground. The groove is loaded with diamond dust or the like whereby there will be an abrasive action on any sapphire held in the groove while

the wheel is rotating. A sapphire to be ground is arranged in the groove to extend longitudinally thereof as shown by the sapphire 87 in Fig. 7.

A plate 88 including a hardened hook-like portion 89 is secured on the outer end of block 75. In the machine the block 75 extends at the side of the grinding wheel 46 and the relation of the parts is such that the hook-like portion 89 extends over the groove 86 of the wheel. Therefore when a sapphire is placed in the groove (as by being passed through the bifurcation in the guide means, later to be described), the rotation of the wheel carries the sapphire with the wheel until the lower or forward end of the sapphire engages the extreme end of said portion or stop means 89 after which further movement of the sapphire with the wheel is controlled until the sapphire is released as will appear.

Attention is directed to the fact that the outside wall of the groove 86 is of somewhat less height than the inner wall thereof. The wheel 46 rotates in the direction indicated by the arrow 90 (Figs. 2 and 4) while the roller 59 rotates in a clockwise direction as shown by the arrow 91 (Figs. 1 and 3). During grinding of a sapphire the roller 59 is being rotated and is in engagement with the sapphire. Therefore as the wheel 46 carries the sapphire against the stop or limiting device 89 the roller 59 is bodily rotating the sapphire and the action of the roller tends to move the sapphire toward the inner wall of the groove. Therefore as the wheel 46 is rotating under the sapphire and the latter is being rotated about its longitudinal axis by the roller 59 it will be clear that the sapphire will be subjected to a grinding action on all its sides and will be ground into a cylindrical shape.

A suitable liquid, as water, to wash away cut material and prevent clogging of the grinding wheel is supplied to the wheel during a grinding operation. For this purpose a tube 92 is connected with the container 35 to receive liquid therefrom and the tube delivers the liquid to the grinding wheel in the vicinity of the roller 59. The flow of the liquid is controlled by the setting of a valve 93 and preferably the liquid is fed drop by drop or in a very thin stream. A guide 94 may be mounted as by having a portion 95 thereof secured to the top of the gear box 68 and the guide includes a bifurcated portion 96 arranged over the wheel 46 and with the opening through such portion 96 arranged over the groove of the wheel. With this arrangement sapphires may be fed to the groove 86 through the opening in the guide portion 96.

Bracket 74 includes an extension 97 having a leg-like portion 98 mounted to turn on the outer end portion of the shaft 30. Fixed to the shaft 30 at the inner side of the member 27 is a collar 101 having a pin 102 extending radially therefrom. Adjacent said collar a block 103 is mounted on said shaft to turn thereabout and such block carries a pin 104 at its outer end and a pin 105 intermediate its ends. A coil spring 106 has its respective ends connected with the pins 102 and 104 and constantly tends to draw said pins toward one another and thus to move the block 103 in a counterclockwise direction about the shaft 30.

Fixed to the outer end of the block 103 is an arm 107, the arm being secured to the block as by screws 108, and said arm includes an upstanding portion 109 extending along the side of the block 75 and at its upper end carrying a tube-

like part 110. Part 110 is aligned with the groove 86 of the grinding wheel when the parts are as in Figs. 7 and 9 and the function of such part will later appear.

It is noted that the arm 111 of the bifurcated portion of the guide 94 is somewhat shorter than the other arm of such portion. This arrangement is provided since if a sapphire fed to the wheel is of unusual diameter or of odd shape it may become embedded in the surface of the roller 59 and be carried out of the groove 86 by the roller during rotation of the latter. Should this happen the sapphire will not be scraped off the roller by the guide arm 111 but will be again carried into the groove by the roller and be scraped therefrom by the inner wall of the groove and thus returned to the groove for grinding.

Cam 73 includes three finger-like portions 112, 113 and 114 equally spaced and arranged radially with respect to the shaft 70 mounting the cam. The body of the cam between the finger-like portions thereof has three slightly inclined surfaces 115, 116 and 117 inclining respectively from the portion 112 to the portion 113, from the portion 113 to the portion 114 and from the portion 114 to the portion 112. The cam is rotated in the direction indicated by the arrow 118 in Fig. 2 and obviously the roller 79a is in said figure against the lowest part of the cam surface portion 115.

With the parts in the indicated positions the stop 89 is partly within the groove 86 in the wheel 46 and any sapphire (as the sapphire 87 of Fig. 7) within the groove will have its lower or forward end against the stop 89. Thus as the grinding wheel is rotating in the direction above indicated it will tend to carry the sapphire with it and to throw the sapphire out of the groove. The stop 89 keeps the sapphire from moving with the wheel and the roller 59 prevents the wheel from throwing the sapphire out of the groove as the wheel revolves. When the roller 79a and the cam 73 are related as shown the stop is in its uppermost position and maintains the sapphire in position under the upper edge portion of the roller 59 as seen in Fig. 7 wherein the roller is shown in dotted lines.

As the grinding operation proceeds, a sapphire having been placed in the groove 86, the cam 73 is moving and as it progresses the roller 79a is gradually raised and the lever comprising the arms 77 and 78 is rocked about the shaft 30 moving the bracket 74 and thus the stop 89 downwardly to permit the sapphire to be gradually fed under the roller toward the lower end thereof. Finally as the grinding is completed one of the finger-like cam portions 112, 113 and 114 engages the roller 79a rocking the same sharply outwardly with the result that the lever portions 77 and 78 are rocked in like manner and carry the block 75 and the stop 89 with them permitting the ground sapphire to then move bodily with the wheel 46 and the latter throws the sapphire downwardly and outwardly and the sapphire passes into the tube 110. Thereafter the sapphire is to be sharpened for use in sound recording or in any other connection as desired.

Thus while the sapphires are fed to the machine one at a time by hand or otherwise, the cam 73 having three fingers the stop 89 is moved from cooperating relation with the wheel or the groove of the wheel three times during each complete revolution of the cam. Obviously the number of finger-like portions on the cam will depend on the speed of rotation of the cam and the

relation of such speed to the speed of rotation of the other parts of the machine.

On loosening of nut 57 the roller 59 may be swung to an out of the way position as shown by the dotted lines in Fig. 2. Arm 107 may move independent of any movement of the bracket 74 when the arm is moved away from the block 75 but the constant tendency of the spring 106 is to keep the arm 107 in position with the tube 110 adjacent the plate 88. As the cam acts to move the bracket 74 and the plate 88 with stop 89 downwardly the block 75 will engage arm portion 109 and cause the tube 110 to be moved downwardly against the action of the spring 106. Pin 105 carried by the block 103 is a stop or limiting device as when such pin engages the pin 102 on the collar 101 the spring 106 can move the said block no further about the shaft.

The hook shape of the stop 89 serves to prevent riding of a sapphire upwardly out of the groove 86 by contact with the plate 88. Obviously on loosening of the screws 29 in the bearing-like members 27 and 28 the shaft 30 and the entire assembly thereon may be adjusted relative to the wheel 46 and guide 94. The slot 80 in the lever arm 78 provides for adjustment of the lever relative to the block 75 and to the shaft 30 whereby to have the cam 73 move the stop 89 in desired relation to the roller 59 whereby to have the sapphire properly presented to the grinding wheel.

In the modification shown in Fig. 12 the grinding wheel is designated 120 and has a corner portion of its periphery removed providing what is best described as an annular notch 121 to receive the sapphire 122 to be ground. The sapphire will be engaged and rotated by the roller 123. It is to be understood that wheel 120 may replace wheel 46 above described and that roller 123 is the same as the roller 59 previously described. While notch 121 is not a true groove as is the groove 86 in wheel 46 yet the purpose is the same in each instance and the word "groove" as used in the following claims is intended to cover the construction of Fig. 12 as well as that of the other figures and such word is not to be read as limiting the claims to a construction embodying a true groove.

Having thus set forth the nature of my invention, what I claim is:

1. In a machine for grinding sapphires for use in the making of sound recording styli, a grinding wheel, means for rotating said wheel, said wheel having a groove therein of a width greater than the diameter of a sapphire to partly receive the sapphire to be ground, a stop to prevent bodily movement of the sapphire with the wheel, means for bodily rotating the sapphire in said groove in a direction substantially transverse to the direction of rotation of the wheel, a movable support mounting said stop for movement of the latter into and out of stopping relation with the sapphire in the groove, and means for moving said support to carry the stop out of stopping relation with a sapphire in said groove on completion of the grinding of said sapphire.

2. In a machine for grinding sapphires for use in the making of sound recording styli, a grinding wheel, means for rotating said wheel, said wheel having a groove therein to partly receive a sapphire to be ground, a stop to prevent bodily movement of the sapphire with the wheel, means for rotating the sapphire in said groove in a direction transverse to the direction of rotation of said wheel, a movable support mounting said

stop for movement of the latter into and out of stopping relation with the sapphire in the groove, and cam means for periodically moving said support to carry the stop out of stopping relation with the sapphire in said groove.

3. In a machine for grinding sapphires for use in the making of sound recording styli, a grinding wheel, means for rotating said wheel, said wheel having a groove therein to partly receive a sapphire to be ground, a stop to prevent bodily movement of the sapphire with the wheel, means for bodily rotating the sapphire in said groove in a direction transverse to the direction of rotation of the wheel, a movable support mounting said stop, a spring normally urging said support into position disposing said stop in stopping relation with a sapphire in said groove, and means including cam means for moving said support to carry the stop out of said stopping relation on completion of the grinding of a sapphire.

4. In a machine for grinding sapphires for use in the making of sound recording styli, a grinding wheel, means for rotating said wheel, said wheel having a groove therein to partly receive a sapphire to be ground, a stop to prevent bodily movement of the sapphire with the wheel, means for bodily rotating the sapphire in said groove in a direction transverse to the direction of rotation of the wheel, a movable support mounting said stop, a spring normally urging said support into a position disposing said stop in stopping relation to a sapphire within said groove, means for moving said support to carry the stop out of said stopping relation on completion of the grinding of the sapphire, and said last means including a cam driven in timed relation to said grinding wheel.

5. In a machine of the character described, a grinding wheel having a groove to receive a sapphire to be ground, a stop means for limiting movement of a sapphire with the wheel and holding such sapphire in grinding position in said groove, a roller for engaging and rotating a sapphire about its own longitudinal axis while in said grinding position, means mounting said stop, a cam engaging said means and operable through it to move said stop and permit the wheel to carry the sapphire out of grinding position, and means for operating said cam in predetermined timed relation.

6. In a machine of the character described, a grinding wheel having a groove in its peripheral edge, a guard extending partly over said wheel and including a portion having a slot in alignment with said groove and through which sapphires may be fed into the groove, a roller for engaging a sapphire in said groove and rotating such sapphire about its own longitudinal axis, said groove having a high side wall and said guard having an opening in its side portion remote from said wall, and means rotating said roller in a direction to carry its sapphire engaging portion toward said wall whereby should a sapphire become embedded in the roller it will be carried about with the roller and through such opening in the guard and back into the groove to be scraped from the roller by said high groove wall.

7. In a machine of the character described, a shaft, a grinding wheel on said shaft, a movable stop associated with said wheel for engagement by a sapphire to be ground and adapted to hold the sapphire against movement with the wheel, a roller mounted for engagement with a sapphire held by said stop for bodily rotating said sapphire on the wheel, means for rotating said shaft, means for rotating said roller from said shaft, a cam for periodically moving said stop out of stopping relation with a sapphire on said wheel, and means driving said cam from said shaft.

8. In a machine of the character described, a shaft, a grinding wheel on said shaft, a movable stop associated with said wheel for engagement by a sapphire to be ground and adapted to hold the sapphire against movement with the wheel, a roller mounted for engagement with a sapphire held by said stop for bodily rotating such sapphire on the wheel, means for rotating said shaft, means for rotating said roller from said shaft, a cam for periodically moving said stop out of stopping relation with a sapphire on said wheel, a spring for moving said stop back to position on release by said cam, means driving said cam from said shaft, and a speed reduction gearing in said last drive means.

9. In a machine of the character described, a grinding wheel having a groove to receive a sapphire to be ground, a stop means for limiting movement of a sapphire with the wheel and holding such sapphire in grinding position in said groove, a roller for engaging and rotating a sapphire about its own longitudinal axis while in said grinding position, means mounting said stop, a cam engaging said means and operable through the same to move said stop and permit the wheel to carry the sapphire out of grinding position, means for operating said cam in predetermined relation, and an adjustable means whereby such timed relation may be varied.

FRANK L. CAPPS.
